UNITED STATES PATENT OFFICE.

DOUGLAS LOWE CAMPBELL, OF WINNIPEG, MANITOBA, CANADA.

BUILDING CONSTRUCTION.

Application filed July 29, 1922. Serial No. 578,447.

To all whom it may concern:

Be it known that I, DOUGLAS LOWE CAMPBELL, of the city of Winnipeg, in the Province of Manitoba, Canada, have invented 5 certain new and useful Improvements in Building Constructions, of which the following is the specification.

The invention relates to improvements in building construction and an object of 10 the invention is to provide forms whereby a cement building can be quickly erected, the inner and outer walls of the building being shot by utilizing what is known as a cement gun to apply the cement or gunite as it is 15 commercially known.

A further object of the invention is to provide duplicate forms which can be readily set up in proper relation, one to the other, and which after the inner wall has 20 been shot and sufficiently set can be readily removed for further operations.

A further object of the invention is to provide forms which permit of the effective reinforcing, bonding and tying in of the 25 walls and whilst permitting of the removal of the forms at the proper time.

A further object of the invention is to provide wall forms which are constructed such that they provide spaced cement pilasters and headers, connecting the pilasters, 30 in the finished wall.

A still further object of the invention is to provide a wall construction, embodying pilasters formed in the wall, wherein nailing 35 cleats are moulded in the pilasters for carrying the outside furring strips.

A still further object of the invention is to provide new and novel means for spacing and fastening the wire mesh utilized in the 40 wall structure.

A still further object of the invention is to provide a type of wall form which can be utilized as a floor form and generally to provide a new and improved method of 45 constructing and handling forms whereby a cement building can be expeditiously and cheaply constructed and the forms of a unit and interchangeable nature and such that they can be readily removed and utilized in 50 further building operation.

With the above more important objects in view the invention consists essentially in the arrangement and construction of parts here-

inafter more particularly described and later pointed out in the appended claims, 55 reference being had to the accompanying drawing in which:

Fig. 1 is an exterior view of the wall showing the forms which I employ.

Fig. 2 is a vertical sectional view at 2—2' 60 Fig. 1 and showing the inner cement wall and floor completed.

Fig. 3 is a horizontal sectional view at 3—3' Figure 1.

Fig. 4 is an enlarged detailed horizontal 65 sectional view through a portion of the wall showing the spacing strip utilized.

Fig. 5 is a vertical sectional view at 5—5' Figure 3.

Fig. 6 is an exterior view of the wall, 70 parts being broken away to expose construction.

Fig. 7 is a vertical sectional view through the completed wall, the section being taken at 7—7' Fig. 6.

Fig. 8 is a horizontal sectional view through the completed wall, the section being taken at 8—8' Fig. 6.

Fig. 9 is a perspective view of the staple and spacer which I employ.

In the drawings like characters of reference indicate corresponding parts in the several figures.

In the following description of this invention I have only shown and described 85 the wall construction from the ground to the first floor as in the continuation of the wall above the first floor the operation is duplicated.

The foundation 1 of the building is of 90 cement or concrete and is poured in the usual manner and the ground floor 2 is shot as a continuous operation, due care being taken to place reinforcements and especially wire mesh anchors tying the wall 95 to the foundation as indicated at 3.

For the purposes of erecting the wall I provide a plurality of similar wall panels 4, these panels comprising substantially rectangular frames each formed from side 100 boards 5 and 6 and a connecting top board 7 and the sides of the frame are connected by suitably spaced horizontal braces 8, 9 and 10 and angularly disposed pairs of crossed bars 11 and 12. The boards 5, 6 105 and 7 are positioned angularly so that the

frame flares outwardly, this permitting of the ready withdrawal of the panels as later described.

5 The braces 11 and 12 are toed into the corners formed at the juncture of the horizontal braces and the side bars 5 and 6. Each panel is a rigid structure, the parts being nailed, screwed or otherwise permanently fastened together.

10 When the wall is to be erected the required number of panels are placed in an upright position on the foundation, the sides of the panels being spaced apart a predetermined distance sufficient to provide 15 a space for a column or pilaster as later described. After the panels have been set up and suitably supported by bracing I nail or otherwise fasten spacers 13 to the outer edges of the adjoining panel bars 5 and 6 20 and also nail or otherwise secure a horizontal header board 14 to the top ends of the panels, this board butting the upper ends of the spacers 13. Further, I fasten a plurality of horizontally disposed tie cleats 15, 25 16 and 17 to the panels, these being nailed to the horizontal braces 8, 9 and 10. Having completed this work I then close the inner sides of the panels by nailing there- 30 to closure sheets 18 of metal or heavy roofing paper and it is here to be particularly observed that this roofing paper does not extend across between the adjacent uprights 5 and 6.

35 Suitably spaced nailing blocks 19 are tacked to the inner sides of the spacers 13, these blocks having inclined sides and ends so that they will become anchored in the concrete afterwards directed against the forms and as later described. These nail- 40 ing blocks are spaced approximately 16 inches apart throughout the height of the spacers and to the nailing blocks I anchor vertically disposed metallic rods 20, to which the wire mesh 21 is tied. The wire 45 mesh 21 passes to the inner side of the panels and is spaced from the closure plates 18 by substantially V-shaped metallic strips 22 fastened to the inner edges of the boards 5 and 6. The shape of these strips is best 50 shown in Fig. 4 of the drawings.

55 Obviously, by the above arrangement I can firmly hold the wire mesh in place as the tie wires 23 connecting the wire mesh to the rods effectively holds the mesh against the strips 22 and in spaced relationship to the plates 18.

60 The above completes the description of the various parts set up in connection with the wall between the ground floor and the first floor. Above this the form structure is duplicated and it will be observed that the header boards 14 space the panels above from those below.

65 Panels can also be utilized for the floor, the panels being set in the horizontal posi-

tion instead of the vertical and being supported by suitable braces as indicated at 24.

The lower edge of the wire mesh is tied to the foundation by the anchors 4 herein- 70 before mentioned.

At the present time there is on the market a machine commercially known as a cement gun and this gun is utilized for shooting a cement composition known as gunite.

75 After the forms have been erected I utilize a cement gun and shoot gunite against the forms. This gunite, indicated at 25, penetrates through the wire mesh to the sheets 18 and also through the wire mesh into the space between the adjoining boards 5 and 6 and also fills into the headers 14 above the top boards 7.

After the walls have been shot the floors are shot as a continuous operation.

80 In say two days' time the forms for the wall can be removed and in approximately three days' time those for the floor can also be removed. In this connection it will be observed that after the horizontal cleats and the spacers have been removed the wall panels can be pulled out from the exterior and the floor panels from below.

85 The inside walls and the underside of the floor can be finished with a putty coat of plaster placed directly on these surfaces, 90 thereby finishing the interior work.

95 After the wall forms have been removed there is left the inner cement wall reinforced by the wire mesh, vertically extending suitably spaced cement pilasters and 100 horizontally extending cement beams, the pilasters and beams being integrally formed with the wall. The pilasters and beams are best shown at 26 and 27 in Figures 6, 7 and 8 of the drawings.

105 The nailing strips 18 remain permanently anchored in the pilasters, their outer faces being exposed after the spacers 8 have been removed. The outer wall is then completed in the following way:

To the strips 19 I fasten horizontally extending furring strips 28 and to these furring strips I nail building paper 29. Outside the building paper I stretch wire mesh 30, the wire mesh being spaced from the building paper and fastened to the furring strips in any suitable manner. I have shown a convenient type of fastening and spacer in Figure 9 of the drawings, which comprises a staple 31 and a bridge strip or 115 spacer 32, suitable end holes being provided in the strip to receive the staple and the spanner part of the strip being provided with a cross channel 33. These bridge strips and the staple are utilized in the following 120 way:

125 The bridge strips are placed between the wire mesh 30 and the furring strips, with the channels 33 receiving the horizontal strands of the wire mesh. Whilst holding 130

the bridge strips in this position the staples are driven into the furring strips and horizontal strands of the wire mesh are caught between the staple and the bridge strip. 5 Obviously, this makes a very effective and convenient fastening.

The space between the building paper 29 and the inner wall is filled in with shavings or mineral wool, indicated at 34.

10 After the wire mesh 30 has been secured in place the outside wall is shot with gunite by utilizing the cement gun, the outer wall being indicated at 35. The gunite penetrates through the wire mesh 30 to the 15 building paper 29 and entirely encloses the wire mesh which reinforces the outer wall and anchors the same to the furring strips through the staples.

The outside wall may be stuccoed or 20 otherwise finished to suit the taste of the owner.

From the above it will be apparent that by this improved form of construction I am 25 able to erect the walls with much saving of time and labor and whilst having a minimum amount of wood in the finished wall and whilst providing a double wall with an air space between.

Further, I form, at the time of shooting 30 the inner wall, cement pilasters or studs and cement headers or beams, which is a very important feature. I might also point out that as the forms are removed 35 there is practically no loss of material in this regard.

What I claim as my invention is:

1. In a cement wall construction, a plurality of similar upright spaced withdrawable moulding panels having outwardly

flaring sides, vertically disposed removable spacers connecting the adjacent sides of the panels, the said spacers and panel sides serving to form vertical reinforcing columns in the moulded wall, and tie cleats detachably secured to the outer sides of the panels and crossing the same and connecting adjoining panels. 45

2. In a cement wall construction, a plurality of similar upright spaced withdrawable moulding panels having outwardly flaring sides, vertically disposed removable spacers connecting the adjacent sides of the panels, the said spacers and panel sides forming vertical reinforcing columns in the moulded wall, and horizontally disposed 55 suitably spaced tie cleats detachably secured to the panels and connecting the same together.

3. In a cement building construction, a substantially rectangular panel presenting outwardly flaring side and top boards, spaced horizontally disposed braces connecting the side boards, pairs of crossed bars within and reinforcing the sides of the panels and closure plates attached to and enclosing the entire inner face of the panel. 65

4. In a cement building construction, a plurality of similar spaced substantially rectangular moulding panels having outwardly flaring sides, spacers connecting the adjacent sides of the panels and spacing strips secured to the sides of the panels and extending inwardly therefrom. 70

Signed at Winnipeg this 14th day of 75
June 1922.

DOUGLAS LOWE CAMPBELL.
